DESIGN FOR A VISIBLE REFERENCE HOLDER

Conrad C. Meilicke, Chicago, Ill.

Application October 11, 1943, Serial No. 111,340

Term of patent 14 years

To all whom it may concern:

Be it known that I, Conrad C. Meilicke, a citizen of the United States, residing at Chicago, in the county of Cook and State of Illinois, have invented a new, original, and ornamental Design for a Visible Reference Holder, of which the following is a specification, reference being had to the accompanying drawing, forming part thereof.

In the drawing:

I claim:

The ornamental design for a visible reference holder, as shown.

CONRAD C. MEILICKE.
